UNITED STATES PATENT OFFICE

HENRY SHPETNER, OF NEW YORK, N. Y.

BAG-LOCK

1,148,999.

Specification of Letters Patent.

Patented Aug. 3, 1915.

Application filed May 25, 1915. Serial No. 30,313.

To all whom it may concern:

Be it known that I, HENRY SHPETNER, a citizen of the United States, and a resident of the city of New York, borough of Manhattan, in the county and State of New York, have invented a new and Improved Bag-Lock, of which the following is a full, clear, and exact description.

This invention relates to locks and particularly to an improved lock for bags, satchels and the like, and has for an object to provide an improved structure which cannot be accidentally opened.

Another object in view is to provide in a single combination or structure a plurality of independent locking features which coact for holding the frame of a bag together when the locking structures are in their locked position.

20 In the accompanying drawings:—Figure 1 is a side view of the upper part of a bag showing a lock embodying the invention applied thereto; Fig. 2 is a top plan view of the lock and associated parts shown in Fig. 1; Fig. 3 is a side view of the lock shown in Fig. 1 and part of the frame, the lock being partially unfastened; Fig. 4 is a sectional view through Fig. 1 on line 4—4, the same being on a slightly enlarged scale.

30 Referring to the accompanying drawings by numerals, 1 indicates the bag which may be of any suitable construction, and 2 a frame which may be of any suitable construction, the frame being formed in two parts and hinged together in the usual manner of frames of this kind. Heretofore interlocking knobs and other means or catches have been provided for locking the parts of the frame together, but such means may sometimes become disengaged, whereupon the bag will open without the knowledge of the owner. To overcome this objection the construction disclosed in the drawings provides means which cannot accidentally become 40 disengaged, as there are a plurality of independent locking structures which must successively be operated before the parts of the frame can open.

45 Arranged at any convenient point, preferably centrally of the frame 2, is a catch 3 normally held in the position shown in Fig. 4 by a spring 4, which spring is rigidly secured at 5 to one of the parts of the frame 2. The catch 3 is designed to interlock with 55 the lug or projection 6 and thereby hold the

parts of the frame 2 together. When it is desired to loosen the catch 3 the same must be moved pivotally off of the lug 6 against the action of the spring 4, said spring 4 acting as a pivotal member as well as the 60 spring for controlling the movement of the catch 3.

Journalized on the top of catch 3 is a locking member 7 provided with a flat plate or button 8, a reduced portion 9 and a journal member 10 reduced in comparison with portion 9. Journal member 10 extends loosely through an aperture in catch 3 and is upset or riveted so as to form a head 11. A washer 12 is preferably arranged between 70 head 11 and the catch 3 so as to provide a proper bearing for head 11. Co-acting with the locking member 7 and catch 3 is a pivotally mounted locking structure 13 which straddles the catch 3 and part of the frame 75 2, as clearly shown in Figs. 1 and 4. The upper surface of the locking structure 13 is formed solid except for a longitudinally arranged slot 14 and an enlargement 15, enlargement 15 accommodating the section 9, 80 of member 7 and slot 14 accommodating the plate or button 8 of member 7 when it is desired to unlock the device.

When the parts are arranged as shown in Figs. 1, 2 and 4 and it is desired to open the bag, the button 8 is turned until the same registers with slot 14. The locking structure 13 is then swung out of the way, as for instance, to the position shown in Fig. 3, after which the catch 3 is raised so as to be disengaged from lug 6, whereupon the bag 1 may be easily opened as the same is completely unlocked. From these three operations it will be observed that there are three locking members or features combined in a 95 single locking structure, the various members coacting so that they must be unlocked in a certain succession and must also be locked in a certain succession.

When the catch 3 is engaged with lug 6 100 the parts of frame 2 are locked together, but to insure against the accidental unlocking of catch 3 the locking structure or straddling member 13 is moved to the position shown in Figs. 1 and 4, and then to insure 105 against the accidental movement of member 13 the locking member 7 is turned to the position shown in Fig. 2. The top of the locking structure 13 is preferably slightly bowed so that there will be a slight tension 110

between the button 8, locking structure 13 and catch 3, such tension holding the button 8 against movement. It is evident that even though the button 8 should become loose and fail to remain in the position shown in Fig. 2, the other locking features coacting therewith will continue to perform their functions, whereby the chance of accidental opening of the bag is limited to an absolute minimum without the use of a positive lock requiring a key for its operation, or some other form of locking structure which could not be readily applied and easily operated on a bag structure. In constructing the straddling member 13 one side thereof is cut away at 16 for accommodating the pivotally mounted link and supporting member 17 which is usually called a "pull." The construction of the pull may be varied without departing from the spirit of the invention, but this structure is desirable in that it provides means for more easily opening catch 3 when the parts are in the position shown in Fig. 3.

25 What I claim is:—

1. In a lock for bags, a primary catch for holding the parts of the frame of the bag together, means for preventing said catch from becoming disengaged or unlocked, and 30 a locking member for preventing said means from moving from its locked position.

2. In a lock of the character described, a substantially pivotally mounted catch, a pivotally mounted member overlapping said catch, and a rotatable locking structure arranged on said catch interlocking with said pivotally mounted locking member for preventing movement of the pivotally mounted locking member.

3. In a lock of the character described, a projection on one of the frames of a bag, a locking member arranged on the other member of the frame of the bag adapted to engage said projection for holding said frames together, a member overlapping said locking member and part of said frames, and a movable locking member arranged in the first mentioned locking member, said movable locking member interlocking with said overlapping member.

4. In a lock of the character described, the combination with the parts of a frame, of spring-pressed interlocking members, a straddling member overlapping said spring-pressed interlocking members, and a movable member arranged on said interlocking members for overlapping said straddling member.

5. In a lock of the character described, a primary lock, a second locking member overlapping the primary lock, and a third lock-

ing member mounted on the primary lock overlapping the second locking member.

6. A lock of the character described, comprising a primary locking member, a straddling member overlapping said primary locking member, said straddling member being formed with a slot in the top, and a pivotally mounted locking member arranged on the primary locking member and extending through said slot, said last mentioned locking member being formed with a plate or wing structure adapted to straddle said slot when being moved to a locked position and thereby hold the straddling locking member in position.

7. In a lock of the character described, a primary locking member for holding the parts of a bag frame together, a pivotally mounted straddling member adapted to overlap said primary locking member and part of said frame, and a pivotally mounted auxiliary lock arranged on said primary lock, said pivotally mounted auxiliary lock having a plate or wing structure adapted to overlap said pivotally mounted straddling member for preventing any independent movement thereof when the auxiliary locking member is in a locked position.

8. A lock of the character described, comprising a pivotally mounted catch for holding the parts of a bag frame together, a straddling member overlapping said pivotally mounted catch and part of the frame of said bag, means for pivotally mounting said straddling member on said frame, said straddling member being formed with an opening in the upper part, and an auxiliary locking member journaled on said catch and extending through said opening in said straddling member, said auxiliary locking member being formed with a wing structure adapted to extend beyond said opening when turned to a locked position, whereby the straddling member is locked against independent movement.

9. In a lock of the character described, the combination with the parts of a frame, of interlocking members for holding said parts together, a straddling member overlapping said interlocking members, and a movable member arranged on said interlocking members for overlapping said straddling member.

In testimony whereof I have signed my name to this specification in the presence of two subscribing witnesses.

HENRY SHPETNER.
